UNITED STATES PATENT OFFICE

108,969

DESIGN FOR A HANDBAG

Henri Felmann, Chicago, Ill.

Application January 14, 1938, Serial No. 74,278

Term of patent 3½ years

To all whom it may concern:

Be it known that I, Henri Felmann, a citizen of the United States of America, residing in Chicago, in the county of Cook and State of Illinois, have invented a new, original, and ornamental Design for a Handbag, of which the following is a specification, reference being had to the accompanying drawing, forming part thereof, wherein,

The rear portion of the handbag is identical in appearance to the front.

I claim:

The ornamental design for a handbag, substantially as shown, and described.

HENRI FELMANN.
